PORTABLE AND COLLAPSIBLE BABY BED

Harry L. Ehrenberg, Little Rock, Ark.

Application December 15, 1950, Serial No. 201,043

5 Claims. (Cl. 5—94)

1

This invention appertains to improvements in baby beds or similar articles of furniture.

One of the primary objects of this invention is to provide a collapsible and adjustable baby bed, which is easily converted for use as a traveling bed or play pen for automobiles or other vehicles and which is easily folded for storage.

Another object of this invention is to provide an adjustable article of furniture, which may be converted from a play pen into a baby bed and which is adjustable in height, so that it may be used as a bed for infants of various ages.

And yet another object of this invention is to provide means for pivotally attaching supporting legs to the opposing ends of the bottom side rails of the crib and to provide means for locking the legs in a position parallel to the side rails and in spaced relation with the underside thereof, means being provided for locking the legs in a vertical position or at right angles to the side rails.

A further object of this invention is to provide telescopically arranged side and end slats, which are provided with means for locking the slats in adjusted extended positions.

A further object of this invention is to provide collapsible end structures, which are pivotally carried by the bottom and top side rails, the end structures being easily collapsed to a position interposed between the opposing bottom side rails and the opposing top side rails, so that the crib may be easily transported or stored.

These and ancillary objects and structural features of merit are attained by this invention, the preferred embodiment of which is set forth in the following description and illustrated in the accompanying drawings, wherein:

Figure 1 is a side elevational view of the preferred form of this invention;

Figure 2 is a top plan view;

Figure 3 is a transverse sectional view taken on line 3—3 of Figure 1 showing one of the end structures in elevation;

Figure 4 is an enlarged detail sectional view taken on line 4—4 of Figure 3, exemplifying the means for pivotally attaching the supporting legs to the side rails;

Figure 5 is a side elevational view of the crib, with parts of the top and bottom side rails broken away to show the telescopically arranged slats and means for mounting the slats on the side rails;

Figure 6 is a top plan view of the crib in a collapsed position;

Figure 7 is a transverse sectional view taken

2

on line 7—7 of Figure 5, with the crib in a folded position;

Figure 8 is an enlarged fragmentary sectional view taken on line 8—8 of Figure 5, and,

5 Figure 9 is a fragmentary side elevational view of an automobile, with the crib positioned therein, resting on the back seat.

With further reference to the accompanying drawings, the convertible and collapsible baby bed or play pen 10 is formed from a pair of bottom side rails 12 and 14. Each of the bottom side rails is provided with longitudinally spaced sockets or recesses 16, which are formed in the upper edge of the rails and accommodate the solid ends 18 of tubular slats 20. The tubular slats 20 are mounted vertically on the opposing side rails and are provided with upper open ends 24 for the reception of solid slats 26. The slats 26 depend from the underside of a pair of top side rails 28 and 30, the upper side rails being formed with openings 32 for receiving the socketed upper ends of the slats 26.

The slats 26 are, thus, telescopically arranged with the tubular or sleeve-like slats 20 and the top side rails 28 and 30 are extensibly or telescopically connected to the bottom side rails 12 and 14 to form the opposing side structures of the crib.

Means is provided for locking the slats 20 and 26 in various extended positions, the locking means including bolts or similar headed fasteners 34, which are extended through transverse openings 36 formed in the upper ends of the end slats 38 and 40 on each of the bottom side rails 12 and 14. Longitudinally disposed or axially extending slots 42 are formed in the end slats 44 of the slats 26 and receive the bolts 34, wing nuts 46 being provided to lock the slotted slats 44 in various positions in the end slats 38 and 40 and thereby lock the slats 26 in various extended positions in the tubular slats 20.

A pair of bottom end rails 48 and 50 are provided and form the bottom frame for the opposing end structures, the bottom end rail 50 consisting of complementary bar members 52 and 54 which are hinged together by a hinge 56, the bar members 52 and 54 of the bottom end rail 48 are hinged together at their inner joining ends by a hinge 62. Top end rails 64 and 66 are provided and overlie the bottom end rails, the top end rail 64 including bar members 68 and 70 which are hinged at their inner adjoining ends by a hinge 72. The top end rail 66 includes bar members 74

and 76 hinged together at their inner adjoining ends by a hinge 78.

Means is provided for pivotally attaching the opposing bottom end rails and opposing top end rails to the adjoining ends of the bottom and top side rails, the means including L-shaped angular brackets 80. The vertical flanges 82 of the brackets are affixed by headed fasteners 84 to the inner surfaces of the bottom side rails and top side rails at the opposing ends of each of the side rails. The horizontal flanges 86 of the brackets projecting laterally from the side rails and the horizontal flanges of the top brackets lie in a plane above the upper edges of the opposing top side rails 28 and 30, while the horizontal flanges 86 of the bottom brackets 80 lie in a common plane below the bottom edge or underside of the bottom side rails 12 and 14. Pivot pins 90 are carried by the horizontal flanges 86 and 88 of the upper and lower brackets and engage the outer ends of the bar members for both the bottom end rails and the top end rails. Thus, the bottom and top end rails are collapsible about their hinged points, the outer ends of the bar members of each of the end rails pivoting about the pivots 90 from an open aligned position to a collapsed parallel position, as seen in Figure 6.

As seen in Figure 3, locking means 92 is provided for locking the ends in an open position, the locking means being carried by each of the top end rails and including a locking pin 94 carried by the bar member 68, as seen in Figure 3, and a pivoted latching member 93 carried by the complementary bar member 70 of the top end rail 68. A similar locking means is carried by the opposing top end rails 66.

A pair of bottom members 98 and 100 are attached by hinges 102 at their outer marginal edges to the opposing bottom side rails 12 and 14. A stop 104 is fixed on the underside of the bottom member 100 and projects beyond the inner free marginal edge thereof for seating the opposing edge of the bottom member 98. The bottom members, when in complementary horizontal position, as seen in Figure 3, are adapted to receive and support a mattress or mattress and spring, as desired. Brackets 106 are carried by the bar members 58 and 60 of the bottom end rail 48 and similar brackets are carried by the opposing bottom end rail 50 for supporting the bottom members 98 and 100 in a lowered position. The brackets 106 are provided with projecting horizontal flanges 108 on which the end edges of the bottom members 98 and 100 rest.

Tubular slats 110 extend upwardly from the bottom end rails and are socketed, at their lower ends, in suitable openings or recesses formed in the bar members of the bottom end rails. Slats 112 depend from the bar members of the top end rails and are telescopically arranged in the tubular slats 110, in a manner similar to the telescopic arrangement of the tubular slats 20 and solid slats 26 of the side rails, as exemplified in Figure 5.

Supporting legs 114 are pivotally attached to the opposing ends of each of the bottom side rails and are adapted to be locked in positions parallel to the side rails and in vertical positions at right angles to the side rails. Each of the supporting legs is attached to the ends of the side rails 12 and 14 in an identical manner and, attention is directed to Figure 4, which constitutes a detailed showing of the means for mounting the supporting legs on the side rails.

A mounting block 116 is affixed to the underside of the bottom side rail 12 and is formed with a curved outer end 118 and a flat top wall 120, which is in abutting relation to the underside 5 of the side rail, and a flat bottom wall 122. A right angular recess 124 is formed in the inner end of the block and is defined by flat walls 126 and 128 which are arranged at right angles to each other. A recess 130 is formed in the wall 126 and a similar recess 132 is formed in the wall 128.

L-shaped brackets 134 and 136 have their vertical flanges securely fixed to the opposing sides of the block 116 and are provided with horizontal flanges 138, which overlie the recess 124 and are disposed in parallel relation. A bolt 140 is transversely disposed through the horizontal sections or flanges of the brackets and is provided with a wing nut 142. A longitudinal slot 144 is formed in the upper end of the leg 114 and is disposed on the pin 140. A dowel 146 is formed on the upper end of the leg 114 and is received in the recesses 130 and 132.

Thus, the supporting leg 114 is swingable about 25 the bolt or pin 140 from a horizontal position to a vertical position. When in a vertical position, the dowel 146 is socketed in the socket or recess 130 and, when in a horizontal position, the dowel is received in the socket or recess 132. The dowel 30 serves to rigidify the leg, either in a raised horizontal position or in a lowered vertical position, with the wing nut being provided on the pin or bolt 140 for locking the leg in either position. It will be noted that when the legs are disposed 35 in raised horizontal positions, the side surfaces 146 of the legs will be flush with the bottom walls 122 of the mounting blocks. Thus, the bed may be converted into use as a play pen, with the surfaces 146 of the raised legs serving as supporting feet.

In use, the bed can be seated on a supporting surface, with the bed resting on the surfaces 148 of the legs or the legs can be locked in supporting vertical positions. The legs would be positioned 40 in vertical position, with the dowels 146 socketed in the openings 130, when the device is used as a bed.

When used either as a play pen or bed, the sides and ends are vertically adjustable, due 50 to the telescopic arrangement of the side slats 20 and 26 and the telescopic arrangement of the end slats 110 and 112. The slats may be easily locked in various extended positions by the locking means carried by the end slats 44 and 55.

As seen in Figure 9, the bed may be easily positioned on the back seat of a vehicle, with the supporting legs carried by the bottom side rail 14 locked in a horizontal position parallel to side rail 14 and resting on the seat and the supporting legs carried by the opposing bottom side rail 12 locked in vertical supporting positions and resting on the floor. The lowered bottom members 98 and 100 will thus be disposed in a horizontal plane and the slats 26 and 112 may be entirely nested within the tubular slats 20 and 110 and locked in such positions.

As seen in Figures 6 and 7, the bed is easily 70 folded by raising the bottom members 98 and 100 about their hinges 102, finger openings 150 being provided and formed adjacent the free side edges of the bottom members, so that the bottom members may be easily raised. The locking means 92 is then released, so that the end 75 rails may be moved about the hinges, connecting

the inner adjoining ends of the bar members of each of the end rails together. The opposing sides are then moved together, as seen in Figure 6. If desired, the legs may be locked in horizontal positions for further compactness or may be left in vertical positions.

Having thus described this invention, what is claimed is:

1. A collapsible baby bed comprising a pair of bottom side rails, a pair of top side rails overlying the bottom rails, telescopically arranged slats connecting the bottom side rails to the top side rails, means for locking said slats in adjusted positions, a pair of bottom end rails pivotally mounted on the adjoining ends of the bottom side rails, a pair of top end rails pivotally mounted on the adjoining ends of the top side rails, said bottom and top end rails being each made up of a pair of bar members hinged together for collapsed movement inwardly between the bottom and top side rails, extensible slats connecting the top and bottom end rails, a pair of bottom members hinged carried by the bottom side rails, means for retaining the bottom members in a horizontal cooperating position for the reception of a mattress, supporting legs pivotally carried by the opposing ends of each of the bottom side rails and means for selectively locking said legs in positions parallel with the side rails or in extended positions at right angles to the side rails.

2. A collapsible baby bed comprising a pair of telescopic sides and telescopic ends, said ends having hingedly connected sections, means pivotally attaching said sections to the sides, a pair of complementary bottom members hingedly carried by the sides, means for retaining the bottom members in aligned horizontal positions for supporting a mattress, means for locking said sides and ends in selected extended positions, supporting legs pivotally attached to the sides, means for selectively locking said legs in horizontal or vertical positions.

3. A collapsible baby bed comprising a pair of telescopic sides and telescopic ends, said ends having hingedly connected sections, means pivotally attaching said sections to the sides, a pair of complementary bottom members hingedly carried by the sides, means for retaining the bottom members in aligned horizontal positions for supporting a mattress, means for locking said sides and ends in selected extended positions, supporting legs pivotally attached to the sides, means for selectively locking said legs in horizontal or vertical positions, said last means including supporting blocks fixed to the sides, each of said blocks being partially cut away to form a recess having straight walls in right angular relation, each of said walls having a socket formed therein, means pivotally attaching the upper ends of the legs in the recesses, and dowels formed on the upper ends of the legs and selectively engageable in the sockets.

4. A collapsible baby bed comprising a pair of telescopic sides and telescopic ends, said ends having hingedly connected sections, means pivotally attaching said sections to the sides, a pair

of complementary bottom members hingedly carried by the sides, means for retaining the bottom members in aligned horizontal positions for supporting a mattress, means for locking said sides and ends in selected extended positions, supporting legs pivotally attached to the sides, means for selectively locking said legs in horizontal or vertical positions, said last means including supporting blocks fixed to the sides, each of said blocks being partially cut away to form a recess having straight walls in right angular relation, each of said walls having a socket formed therein, means pivotally attaching the upper ends of the legs in the recesses, dowels formed on the upper ends of the legs and selectively engageable in the sockets, said means pivotally attaching the legs including brackets fixed to the opposing sides of the blocks and projecting past the recesses, and a pin transversely disposed through the projecting portion of each bracket, each of said legs having a longitudinal slot receiving said pin, whereby the leg is swingable about the pin for selectively positioning the dowel in the socket to which the leg is attached.

5. A collapsible baby bed comprising a pair of telescopic sides and telescopic ends, said ends having hingedly connected sections, means pivotally attaching said sections to the sides, a pair of complementary bottom members hingedly carried by the sides, means for retaining the bottom members in aligned horizontal positions for supporting a mattress, means for locking said sides and ends in selected extended positions, supporting legs pivotally attached to the sides, means for selectively locking said legs in horizontal or vertical positions, said last means including supporting blocks fixed to the sides, each of said blocks being partially cut away to form a recess having straight walls in right angular relation, each of said walls having sockets formed therein, means pivotally attaching the upper ends of the legs in the recesses, dowels formed on the upper ends of the legs and selectively engageable in the sockets, said means pivotally attaching the legs including brackets fixed to the opposing sides of the blocks and projecting past the recesses, a pin transversely disposed through the projecting portion of each bracket, each of said legs having a longitudinal slot receiving said pin, whereby the leg is swingable about the pin for selectively positioning the dowel in the socket of the bracket to which the leg is attached, each of said blocks having a flat bottom wall and the outer side surface of each leg being flush with the bottom wall of each block when the leg is in a horizontal position.

HARRY L. EHRENBURG.
